UNITED STATES PATENT OFFICE.

SHINKICHIRO SHIMA, OF LOS ANGELES, CALIFORNIA.

STRAND AND CABLE SUSPENSORY SUPPORTER.

1,284,158.

Specification of Letters Patent. Patented Nov. 5, 1918.

Application filed June 13, 1918. Serial No. 239,812.

To all whom it may concern:

Be it known that I, SHINKICHIRO SHIMA, a subject to the Japanese Empire, residing at Los Angeles, in the county of Los Angeles 5 and State of California, have invented new and useful Strand and Cable Suspensory Supporters, of which the following is a specification.

My invention relates to devices for hanging cables and strands of telephone or telegraph wires to suitable supporting means, usually a heavy wire when suspended on 10 streets.

One object of this invention is to provide 15 a device which can easily be secured to a suitable place.

Another object is to provide a device which can easily be opened as well as closed for removing or placing more material in 20 the device.

Another object is to provide a device which will not open by any shaking to which such devices are usually subjected.

Other objects will appear from the following description and appended claims as well as from the accompanying drawing, in which—

Figure 1 is a perspective view of the device in opened position.

Fig. 2 is a cross section on line 2—2 of Fig. 1.

Fig. 3 is a perspective view of the device as applied in use.

In Fig. 1, 4 designates the body of the device, preferably of sheet metal, but any other similar material, even fabric may be used, as will easily be understood from the following description. The body 4 consists of a strap of suitable width, both ends rolled 40 in, as indicated at 5 and 6. The overlapping ends 9 are locked together by a narrow strap 7, of which the ends 8 are inserted through suitable slots 10, see Fig. 2, through both layers, the body and the overlapping parts, and then clamped toward the material of the body or overlapping parts. The rolled-in end 5 serves as a sleeve or hinge for the wire 11, which is bent on both ends outside of the rolled-in end 5, thereby 45 interlocking the rolled-in end 5 and the wire 11, the wire turnably within the rolled-in end. Both ends of the wire are hook-shaped as indicated at 12, swinging radially to the axis of the wire. Another wire is doubled 50 and bent to form the supporting hook 14 with the bent end 13. This hook 14 is

parted at a suitable point to project transversely to the hook. The transverse ends of the hook are disposed in the rolled-in end 6, extending a suitable distance through the 60 rolled-in end 6 at both sides, as indicated at 15 and 16, the end 15 being long enough to allow the engaging of the engaging hook 12, one of the two on the wire 11, the other engaging hook 12 engaging over the end 16. 65 To prevent the engaging hooks 12 from slipping from the ends 15 and 16 of the main or supporting hook, the ends 17 are bent upwardly, leaving space enough to allow the engaging hooks 12 to easily pass between the 70 bent ends 17 and the rolled-in ends 6.

In use, the main or supporting hook 14 is hooked over the heavy wire 18, and the strand of telephone wires or similar articles are placed within the body 4, as illustrated in Fig. 3.

As telephone- or telegraph-wires, lately placed in strands and suspended in the manner as illustrated in Fig. 3, are very often to be exchanged or repaired, it is necessary to 80 provide devices of this nature, which can easily be opened and closed, still preventing a falling apart. For this reason, I provide the device with the wire 11, which turns easily within the rolled-in end 5. A shifting 85 of the side with the rolled-in end 5 against the side with the rolled-in end 6, will always just cause the engaging hooks to swing around the ends 15 and 16 of the main hook, as will easily be understood. For 90 taking the device apart, it is necessary to press the side with the rolled-in end 5 toward the side with the rolled-in end 6 and then turn the engaging hooks on the wire 11 to disengage from the ends 15 and 16. Such 95 taking apart can be accomplished without taking the main hook 14 from the heavy wire 18.

Having thus described my invention, I claim:

1. In a device of the class described, a flexible body-member being rolled in at both ends, a supporting hook made of a doubled wire spread apart at a suitable point to swingably engage with one rolled-in end of 105 the body, and engaging hooks formed on another wire swingably engaging with the other rolled-in end of the body, the engaging hooks being formed on the second named wire swinging radially to the axis of the 110 wire so as to hook over the ends of the first named wire in the opposite end of the body.

2. In a device of the class described, a flexible body member being rolled-in at both ends, a supporting hook made of a doubled wire spread apart at a suitable point to swingably engage with one rolled-in end of the body, the ends of this wire projecting through the rolled end and having each a bent end spaced from the rolled-in end of the body, and engaging hooks formed on another wire swingably engaging with the other rolled-in end of the body, the engaging hooks being formed on the second named wire swinging radially to the axis of the

wire so as to hook over the ends of the first named wire in the space between the first 15 named rolled-in end of the body and the bent ends of the first named wire for engaging the two rolled-in ends of the body, all substantially as described.

In testimony whereof I hereunto affix my 20 signature in the presence of two witnesses.

SHINKICHIRO SHIMA.
